ATTORNEYS

UNITED STATES PATENT OFFICE.

JOSEPH EHRHARD, OF CURTIS, OKLAHOMA.

POTATO SLICER.

Application filed March 29, 1922. Serial No. 547,710.

To all whom it may concern:

Be it known that I, JOSEPH EHRHARD, a citizen of the United States, and a resident of Curtis, in the county of Woodward and State of Oklahoma, have invented a new and Improved Potato Slicer, of which the following is a full, clear, and exact description.

This invention relates to improvements in potato slicers, an object of the invention being to provide a device of this character for slicing potatoes or similar vegetables, which will cut the potatoes or other articles to be sliced into fine pieces, and which is provided with improved means for slicing the potatoes both longitudinally and transversely.

Another object is to provide a potato slicer which will be simple and practical in construction, strong, durable and efficient in use, sufficiently light in weight so that it can be readily carried about, and comparatively economical to manufacture.

With these and other objects in view, the invention consists in certain novel features of construction and combinations and arrangements of parts as will be more fully hereinafter described and pointed out in the claims.

In the accompanying drawings:

Figure 1 is a view in side elevation of my improved potato slicer;

Figure 2 is a top plan view thereof with parts broken away and in section for clearness, being taken on the line 2-2 of Figure 1;

Figure 3 is a view in longitudinal section through the device;

Figure 4 is a view in transverse section on the staggered line 4-4 of Fig. 1; and

Figure 5 is a similar view on the staggered line 5-5 of Figure 1.

Referring in detail to the drawings, I have used the reference numeral 1 to designate a supporting base for my improved potato slicer. This base includes perforated feet 2 having openings therein adapted to receive securing devices for removably securing the base to any suitable support. The base likewise includes a pair of curved arms 3 supporting the cylindrical body 4 of the machine. This cylindrical body rests upon its side on the base.

I have used the reference numeral 5 to designate the end wall of the cylindrical body or container 4. The other end of the

body is open. A bushing or bearing sleeve 6 secured to the wall 1 cooperates with an upstanding bracket 7 at the end of the base 1 to provide mounting for a shaft 8, extending centrally and longitudinally through the body. A crank handle 9 is provided at the outer end of the shaft for manually turning the same.

A pair of rotary knives 10 fixed to the shaft at the open end of the body 4 are adapted to cut potatoes fed to them into slices, and outstruck teeth 11 integral with one of the knives are adapted to sever the sliced pieces of potato as they pass between the knives so that the potato is cut first into slices and then into smaller pieces. The particular manner of attaching the blades to the shaft is of course immaterial, but I prefer to provide a shaft with a squared end 12 adjacent the crank handle, and to provide the blades 10 with lateral extensions 13 which are bolted to the shaft, as indicated at 14.

It will be apparent that it is necessary to provide some means for introducing the potatoes into the body or casing of the machine, and also to provide means for feeding the potatoes to the knives. The introduction of potatoes into the body is accomplished by the provision of a hinge door 15 in the top side of the container 4, hinged as indicated at 16, and adapted to be opened to permit the dropping of potatoes into the body of the container.

A follower, designated by the reference numeral 16' is in the form of a plate shaped substantially in conformity with the internal walls of the cylinder and including at its sides a pair of laterally extending lugs 17 which ride in longitudinal channels in the side wall of the container, said channels being formed by slotting the container and turning the material at the edges of the slots inwardly, as indicated at 18. Movement of the feeder or follower 16' longitudinally of the container will operate to positively feed potatoes therein to the cutting knives 10 and the teeth 11.

The actuating means for the follower consists of a substantially U shaped handle 19 straddling the container 4 and pivotally secured at its lower extremities to the base 1, as indicated at 20. The legs of the handle have a slot and pin connection 21 with the lugs 17 so that pivotal movement of the

handle effects longitudinal movement of the follower 16' within the container to positively feed potatoes to the rotary knives.

In operation, after the device has been attached to a table or other suitable support and the potatoes introduced into the container, the operator places one hand upon the handle 19 and one upon the handle 9 simultaneously moving the handle 9 to slice the 10 potatoes and the handle 19 to feed potatoes to the knives. The potatoes are delivered between the knives into any suitable receiving vessel which may be provided for their reception.

15 In order to prevent undue turning or rotation of the potatoes in the container and to hold them steady against the action of the knives, I prefer to provide one or more internal ribs 22 extending longitudinally 20 within the container to hold the potatoes against movement.

It is to be understood that while I have illustrated one of the preferred embodiments of the invention, numerous slight changes 25 and alterations might be made in the general form and arrangement of the parts described without departing from the invention; and hence I do not wish to limit myself to the precise details set forth, but shall consider 30 myself at liberty to make such slight changes and alterations as fairly fall within the spirit and scope of the appended claims.

I claim:

1. In a slicing machine of the character 35 described, a cylindrical container, a shaft journaled longitudinally in the container, means for turning the shaft, said container including an open end, and a pair of spaced cutting knives carried by the shaft at the 40 open end of the container, and adapted to slice material fed thereto, one of the knives being provided with laterally projecting teeth adapted to chop the sliced material.

2. In a slicing machine of the character 45 described, a cylindrical container, a shaft

journaled longitudinally in the container, means for turning the shaft, said container including an open end, a pair of spaced cutting knives carried by the shaft at the open end of the container, and adapted to slice 50 material fed thereto, the knife adjacent the end of the container being provided with laterally projecting teeth adapted to chop the sliced material, and a follower movable longitudinally in the container for positively 55 feeding material to be sliced to the knives.

3. In a slicing machine of the character described, a cylindrical container, a shaft journaled longitudinally in the container, means for turning the shaft, said container 60 including an open end, cutting knives carried by the shaft at the open end of the container, and adapted to slice material fed thereto, teeth carried by one of said knives adapted to chop the sliced material, a follower movable longitudinally in the container for positively 65 feeding material to be sliced to the knives, said container having slots in its sides, lugs on the follower riding in the slots, and means connected with the lugs for 70 actuating the follower.

4. In a slicing machine of the character described, a cylindrical container, a shaft journaled longitudinally in the container, means for turning the shaft, said container 75 including an open end, cutting knives carried by the shaft at the open end of the container, and adapted to slice material fed thereto, teeth carried by one of said knives adapted to chop the sliced material, a follower movable longitudinally in the container for positively 80 feeding material to be sliced to the knives, said container having slots in its sides, lugs on the follower riding in the slots, and means straddling the container 85 having a slot and pin connection with the lugs for actuating the follower, said means including a U shaped handle.

JOSEPH EHRHARD.
